UNITED STATES PATENT OFFICE.

LOUIS G. M. WEST, OF BALTIMORE, MARYLAND.

LUBRICATING APPARATUS.

1,086,255.

Specification of Letters Patent. Patented Feb. 3, 1914.

Application filed February 6, 1913. Serial No. 746,627.

To all whom it may concern:

Be it known that I, LOUIS G. M. WEST, a citizen of the United States, residing at Baltimore, in the State of Maryland, have 5 invented new and useful Improvements in Lubricating Apparatus, of which the following is a specification.

My invention relates to apparatus for lubricating the guide rails of elevating machinery or the like and particularly to that type supplying lubricating fluid, at predetermined points in the elevator travel, to suitable lubricant distributors of "lubricators" which are located on the elevator carriages and bear against the exposed faces of the guides to be lubricated.

One object of the invention is to produce an apparatus of the aforesaid type which adapts itself to the elevator side play in such 20 a manner as to furnish at each actuation of the apparatus a substantially uniform quantity of lubricant to the lubricators, thereby eliminating the disadvantageous feature in known apparatus of this type of supplying 25 a continuously varying quantity of fluid more or less dependent upon the lateral displacement of the elevator with respect to the guides.

The invention further contemplates an apparatus 30 whose parts may be readily adjusted to supply the exact amount of lubricating fluid requisite for the particular elevator; whose parts are so constructed and arranged with relation to each other as to reduce to 35 a minimum sudden jars and pounding due to the operation of the apparatus; and further a lubricating apparatus characterized by its rigidity in construction, by its simplicity in operation and parts, and by its reliability 40 for service with a minimum of attention.

In addition to the above desirable features other advantages of my apparatus will appear by reference to the following described drawings which are merely illustrative of 45 one form of my invention, wherein:

Figure 1 is a plan view of my apparatus with certain parts broken away and in section; Fig. 2 is a top view of that portion of the apparatus located on the elevator cage; 50 Fig. 3 is a sectional view taken on line 3-3 in Fig. 1; Fig. 4 is a sectional view through the lubricant collecting pan shown in Figs. 1 and 2; Fig. 5 is a top view of the oil wheel guard shown in Fig. 4; Fig. 6 is an 55 end view of the distributors and the distributing conduits; Fig. 7 is a side view of

the bumper wheel and related parts in the idle position of the lubricating apparatus. Fig. 8 is a plan view of a modified form of apparatus. Fig. 9 is an end-view, partly in section, of the modified form shown in Fig. 8. Fig. 10 is a sectional view through the guard showing the relation of the wiper and disk thereto. Fig. 11 is an end-view, partly sectional, of the parts shown in Fig. 10. Fig. 12 is a top view of the wiper and Fig. 13 is a plan view of the receiving cups leading to lubricators.

Referring in particular to Figs. 1 and 2 a suitable lubricant container or reservoir 1 is carried by an elevator cage (not shown) and is supported thereon by means of a standard 2 (partly broken away) which is in turn fixed to the elevator cross-head (not shown). This reservoir carries suitable lubricant distributors or lubricators 3, similar to the distributors shown and illustrated in my former Patent No. 821,072, issued May 22, 1906, these distributors being suitably fixed to the reservoir as by uprights 4 bolted to suitable lugs 5 on the bottom of the reservoir 1 (Fig. 3). It is to be understood that a lubricant is supplied to the exposed faces of an elevator guide rail (not shown) through these distributors 3 and a collecting 55 or receiving cone 6, preferably incased in a protective casing 7 of glass, is provided with ducts leading to and supplying the various distributors 3, all in a similar manner to the disclosure in the above mentioned patent. The reservoir 1 carries at its top a collecting 60 pan 8, which in turn has fixed to the bottom thereof a drain pipe 9 for directing the lubricant from the bottom of the collecting pan to the collecting and distributing cone 6. 65

The lubricating fluid is drawn out of the tank 1 by a revolving disk 10 and collected therefrom into the collecting pan 8. This disk 10 extends upwardly through a slot (Figs. 1 and 4) in the collecting pan slightly 100 above the bottom of the same, and the oil, as the disk 10 revolves, is thrown by centrifugal force from the disk into the pan; or suitable wipers or collectors may be provided for facilitating removal of the oil 105 from the disk, as for instance wiper 35 (Figs. 10 and 12) whose free end 36 is slotted to straddle the disk 10. The disk is carried by a shaft suitably journaled in hangers 11 extending downwardly into the tank 110 1 from the collecting pan. To the shaft is also fixed a pinion 12 which meshes with a

segmental gear 13 mounted on a shaft 14, this shaft being journaled at one end in an upright from the collecting pan 8 and at the other end in a bracket 15 fixed as shown to 5 the side of the reservoir. The segment extends downwardly through a slot in the bottom of the collecting pan into meshing gear with the pinion 12 for actuating the disk 10. The bracket 15 extends toward the 10 left beyond the reservoir and near the end is pivoted thereto a bell crank 16. One end of this lever carries a buffer or bumper wheel 17, preferably of elastic material such as for instance rubber, and to the other end of the 15 bell crank lever is pivoted a connecting link 18 connecting the lever to a crank arm 19, fixed to the shaft 14; so that by rocking the lever 16 power is transmitted through connecting link 18 and crank arm 19 to the 20 rock shaft 14 which actuates the segmental gear 13 to revolve the disk 10 to supply oil to the collecting pan. The bell crank lever 16 has therein a slot through which projects a stop 20 fixed to the bracket 15, this stop 25 20 serving to limit the rocking movement of the bell crank lever 16 in either direction of rocking movement by engaging opposite ends of the slot. Suitable set screws 21 may be provided and screwed into the lever 30 16 so as to project within the opposite ends of said slot for the purpose of adjusting the maximum rocking movement in either direction. The bell crank lever 16 is also provided with a cut-out portion 22 into which 35 projects the free end of a spring 23, the other end of this being fixed to the bracket 15 in any suitable manner, as by means of a screw. The purpose of this spring 23 is to serve as a cushion means for the lever mechanism 40 40 when the mechanism is being actuated, as shown in Fig. 1, and also as a retractile means to bring the leverage system back to the normal idle position indicated in Fig. 7.

All the parts heretofore described are 45 those carried by the elevator or car. For actuating the disk 10 through the leverage and gearing system above described suitable projections or bumpers are stationed at intervals along the elevator travel in the path 50 of the bumper wheel 17. One of these bumpers 24 is shown in the drawing and is carried by a portion 25 of the guide rail frame work. As the elevator passes this bumper the bumper wheel 17 comes into engagement 55 therewith and the lever 16 is thereby caused to swing in a direction depending upon the direction of the elevator travel, thereby actuating the transmission gearing described above to actuate the disk 10 to supply lubricant to the collecting pan 8, thence from the collecting pan through the conduits 9 to the collecting cone 6 and from there to the various distributors.

It is known that side play is always present 60 in an elevator due to either defects in

the original installation or due to the wear and tear on the elevating apparatus. Should the bumper 24 therefore be mounted rigidly on the guide rail frame, the rocking movement given to the lever 16 and bumper wheel 17 would be continuously varying due to changes in side play, the maximum rocking movement being dependent on the relative lateral positions of the buffer 24 and the bumper wheel 17 at the time the elevator is 70 passing. Such variations in rocking movement would of course result in unequal quantities of lubricant being supplied by the disk 10 to the pan 8, as the quantity supplied at each actuation is more or less dependent upon the number of revolutions made by the disk, and in order to eliminate this disadvantageous feature which may be caused by the side play of the elevator I propose to 75 mount the bumper 24 yieldingly on the guide rail frame work for lateral movement relative thereto and to make this lateral movement great enough to take care of the side play of the elevator. In this manner the lever 16 may be given its maximum rocking 80 movement at each actuation of the apparatus regardless of the variations in the side play. To this end I fix to the portion 25 of the guide rail frame a suitable spring 26 preferably of the form shown, this spring being 85 conveniently secured at its middle point by a set screw 27; and the bumper 24 is provided in its middle portion with a transverse slot through which projects a bolt 28 from the frame work 25 for limiting the lateral 90 movement of the bumper relative to the guide rail. This bolt is provided with a suitable nut and washer for holding the bumper into sliding engagement with the guide rail 95 frame. The spring 26 as shown presses 100 against either end of the bumper 24 to force it toward the right, the extreme limit, its movement in this direction being limited by the bolt 28 coming into engagement with the bumper in the left hand end of the slot.

In the position shown in Fig. 1, the elevator is going in the upward direction and the bumper wheel 17 is now in the maximum rocking position for the upward direction of the elevator. The bumper wheel 17 is just beginning to ride off the cam surface of the bumper 24, and the spring 23 is in tension to bring the parts back to the normal or idle position as shown in Fig. 7. If the elevator were going in the opposite direction, the lever 16 would of course be actuated in the opposite direction and the retractile spring 23 would be bearing against the upper surface of the cut-out portion 22 in the bell crank lever 16, tending to bring the parts back to idle position as shown in Fig. 7. It should be noted that the spring 26 serves a double purpose: first, as means to maintain the bumper in its extreme right hand position to impart to the lever 16 its 110 105 115 120 125 130

maximum movement regardless of any side play of the elevator, and secondly, as cushion means for the apparatus to prevent sudden jars and pounding due to high speed of the elevator and other causes when the bumper wheel 17 strikes the bumper 24. The transverse slot in the bumper 24 is preferably slightly longer than the maximum side play of the elevator in order that there may be a margin of lateral play of the bumper in all lateral positions of the elevator with respect to the guide rail for the spring 26 to serve as a cushioning means at all times.

It will be noted by reference to Fig. 1 that a float 29 is provided with a stem protruding upwardly out of the oil tank to indicate the oil level, this oil level being shown in dotted lines. This stem passes upwardly through a funnel-shaped member 30 which serves as a means for introducing lubricant into the tank 1. A cover 32 of any suitable form is also illustrated for excluding dirt, etc., from the reservoir and collecting pan.

Referring to Figs. 4 and 5, a guard 31 for the oil disk is shown for guarding against the splashing of oil when the disk 10 is driven at a high speed and for directing the lubricant into the collecting pan 8. This guard 31 may be provided with ears 34 (only one being illustrated) cut therefrom and bent inwardly as shown to facilitate the collecting of oil from the disk periphery and directing it down the incline of the thickened portion 33 of pan 8 into the pan. The guard 31 carries the wiper 35, the latter being secured thereto by means of a screw 37.

It is to be noted that the lever arm 16 in the normal or idle position shown in Fig. 7 is in a vertical position; that the crank arm 19 may be provided with a plurality of pivot points (two being shown) to which the connecting link 18 may be connected to vary the throw of the gear segment relative to the throw of the bumper wheel 17; and furthermore the gear segment is symmetrically arranged with respect to the crank arm 19 and made large enough to avoid running off the pinion in the maximum rocking movement for which the apparatus is designed.

The foregoing is illustrative of only one of the many forms which my invention is capable of assuming and it is to be understood that all changes in form that come within the spirit of my invention are intended to be covered by the claims appended hereto. For instance, inasmuch as the number of lifting disks employed in any particular case depends upon the demands for lubricant it may be desirable to provide a plurality of disks, as is illustrated in Figs. 8 and 9 where three disks are shown mounted on a common shaft, and driven by means of a pinion 12' meshing with a segment 13', this segment being mounted in turn on rock shaft 14'. Each disk supplies

lubricant to a collecting pan 8' and from thence to an individual conduit 9' leading downwardly to an individual receiving cup 6', each one of these cups leading to a distributor 3' as shown in dotted lines. 70

I claim as my invention—

1. In an elevator guide rail lubricating apparatus, the combination of a lubricating device adapted to be mounted on the elevator car and an actuator adapted to be mounted 75 on the guide rail or stationary framework, with side play compensating means adapted to maintain said actuator and lubricating device in actuating relation at an actuating point in the travel of the elevator car. 80

2. In an elevator guide rail lubricating apparatus, the combination of devices adapted to be connected to the elevator for supplying lubricant to the guide rail, means adapted to be connected to the elevator for 85 actuating said devices, and means adapted to be connected to the guide rail frame for imparting motion to said actuating means, one of said means being yieldingly mounted at its point of support for lateral movement. 90

3. In an elevator guide rail lubricating apparatus, the combination of a guide rail lubricant distributor adapted to be connected to the elevator, means adapted to be connected to the elevator for supplying lubricant to said distributor, and means adapted to be yieldingly mounted on the guide rail frame for actuating said supply means. 95

4. In an elevator guide rail lubricating apparatus, the combination of a guide rail lubricant distributor adapted to be connected to the elevator, means adapted to be connected to the elevator for supplying lubricant to said distributor, and means adapted to be mounted yieldingly for lateral play on 100 the guide rail frame for actuating said supply means. 105

5. In an elevator guide rail lubricating apparatus, the combination of a guide rail lubricant distributor, a reservoir, means for 110 supplying lubricant from said reservoir to said distributor, all adapted to be located on the elevator, with means adapted to be mounted yieldingly for lateral play on the guide rail frame for actuating said supply means. 115

6. In an elevator guide rail lubricating apparatus, the combination of a guide rail lubricant distributor, a reservoir, a disk revolvably mounted within said reservoir for 120 furnishing lubricant to said distributor, actuating means for said disk, all adapted to be located on the elevator, with means adapted to be mounted yieldingly for side play on the guide rail frame for imparting 125 motion to said actuating means.

7. In an elevator guide rail lubricating apparatus, the combination of guide rail lubricant distributors, a reservoir, a disk revolvably mounted within said reservoir for fur- 130

- nishing lubricant to said distributors, actuating means for rotating said disk from its normally idle position, retractile means for bringing said disk and actuating means back 5 to normal position after operation, all adapted to be located on the elevator, with means adapted to be mounted yieldingly for lateral play on the guide rail frame for imparting motion to said actuating means.
- 10 8. In an elevator guide rail lubricating apparatus, the combination of guide rail lubricant distributors, a reservoir, a disk revolvably mounted within said reservoir for furnishing lubricant from said reservoir to 15 said distributors, spring retracted actuating means for rotating said disk from its normally idle position, all adapted to be located on the elevator, with means adapted to be mounted yieldingly for lateral play on 20 the guide rail frame for imparting motion to said actuating means.
9. In an elevator guide rail lubricating apparatus, the combination of guide rail lubricant distributors, a reservoir, a collecting 25 pan on top of said reservoir draining into said distributors, a disk revolvably mounted within said reservoir for lifting lubricant therefrom to the collecting pan, actuating mechanism for said disk, a spring 30 retracted bell crank lever for imparting motion to said mechanism, all adapted to be located on the elevator, with a laterally movable cushioned bumper mounted on the guide rail frame for actuating said bell 35 crank lever.
10. In an elevator guide rail lubricating apparatus, the combination of lubricant distributors, a reservoir, a collecting pan on top of said reservoir draining into said distributors, a disk revolvably mounted within 40 said reservoir for lifting lubricant therefrom to the collecting pan, means located above and in proximity to said disk for facilitating removal of lubricant therefrom 45 and directing it into said collecting pan,

actuating mechanism for said disk, all adapted to be located on the elevator car, with a laterally movable cushioned bumper adapted to be mounted on the guide rail for actuating said mechanism.

11. In an elevator guide rail lubricating apparatus, the combination of lubricant distributors, a reservoir, a collecting pan on top of said reservoir draining into said distributors, a disk revolvably mounted within 50 said reservoir for lifting lubricant therefrom to the collecting pan, a wiper bearing against said disk for facilitating removal of lubricant therefrom and directing it into said collecting pan, actuating mechanism for said disk, all adapted to be located on the elevator car, with a laterally movable cushioned bumper adapted to be mounted on the guide rail for actuating said mechanism.

12. In an elevator guide rail lubricating 55 apparatus, the combination of means adapted to be connected to the car for supplying lubricant to the guide rail, an actuating device for said means adapted to be located on the car, a bumper adapted to be mounted on 60 the guide rail frame, and an adjustable stop to limit the actuating movement of said actuating device.

13. In an elevator guide rail lubricating 65 apparatus, the combination of means adapted to be connected to the car for supplying lubricant to the guide rail, an actuating device for said means adapted to be located on the car, a laterally cushioned bumper adapted to be connected to the guide rail frame, 70 and an adjustable stop to limit the actuating movement of said actuating device.

In testimony whereof I have hereunto set my hand in presence of two subscribing witnesses.

LOUIS G. M. WEST.
